UNITED STATES PATENT OFFICE.

MATILDA ROSS, OF TACOMA, WASHINGTON.

EMBROIDERY-FRAME AND SUPPORT THEREFOR.

1,110,349.

Specification of Letters Patent. Patented Sept. 15, 1914.

Application filed October 23, 1913. Serial No. 796,946.

To all whom it may concern:

Be it known that I, MATILDA Ross, a citizen of the United States, residing at Tacoma, in the county of Pierce and State of Washington, have invented certain new and useful Improvements in Embroidery-Frames and Supports Therefor; and I do hereby declare the following to be a full, clear, and exact description of the invention, such as will enable others skilled in the art to which it appertains to make and use the same.

The object of this invention is to provide an embroidery frame for holding embroidery work stretched, and consisting of adjustable parts which may be quickly and conveniently assembled and adjusted for securely holding work of various sizes.

A further object is to provide an adjustable support for the embroidery frame for supporting the latter at any desired height above the floor and in any desired position.

In the accompanying drawings wherein is shown an approved embodiment of the invention, Figure 1, represents a top plan view of the adjustable embroidery frame and supporting devices therefor. Fig. 2, represents a side elevation thereof. Fig. 3, represents a detail sectional view through the corner fastenings of the embroidery frame. Figs. 4 and 5, represent perspective views of the parts of the corner fastenings of the embroidery frame separated, and Fig. 6, represents a sectional view on the line 6—6 of Fig. 1.

Referring to the drawings in detail, 1 represents a pair of twin side members of the embroidery frame and 2, a pair of twin end members. Metallic fastening members 3, are secured to the under sides and project outwardly from the ends of the end members 2, the extremities thereof are turned upwardly at 4, as clearly shown in Fig. 5, and slotted at 6. A bolt 7 is positioned through the slot 6, and also through a suitable aperture formed in the L-shaped clamping member 8, and is provided with a suitable wing nut 9, for clamping members 3, and 8, together against the top and bottom of the side members 1, as clearly shown in Fig. 8. It will be understood that the slot 6, in the metallic fastening member 3, permits the end members 2, to be adjusted at various distances apart and secured in adjusted position by means of bolt 7, and wing nut 9. The

inner and top edges of each of the side and end members 1 and 2 respectively, are cut away at 10, and provided with a semi-circular groove 11. Cleats or clamping strips 12, are provided for each side and end member of the embroidery frame and the lower surfaces thereof are shaped in conformity with the cut away portion in the side and end members, whereby said clamping strips 12, will snugly fit over said side and end members and terminate flush with the upper surface thereof. A section of fabric 13, or other work which is desired to be embroidered, is placed between the side and end members and strips 12, and securely clamped into position by the clamping members 14. A supporting leg is provided for supporting one side of the embroidery frame and consists of sections 15, adjustably connected by a bolt 16, and wing nut 17, engaging through an opening in one of the sections 15, and through a slot in the other section, as will be understood. The upper end of the top section 15, is provided with a clamping jaw 18, carrying a clamping screw 19, adapted to secure said jaw upon the adjacent part of the embroidery frame. For supporting the opposite side of the embroidery frame and preventing tilting of the latter, a tripod consisting of legs 20 and vertically adjustable standard 21, is provided and hingedly secured to said embroidery frame by a hinge member 22, and wing nut and bolt fastening 23.

From the foregoing it will be seen that the embroidery frame may be adjusted for holding in stretched condition, embroidery work of various shapes and sizes and also that the embroidery frame is provided with supporting means for holding it at any desired height and in any desired position. It will also be apparent that the parts of the frame and supporting means therefor, may be quickly and conveniently disassembled and packed so as to occupy very small space.

Having thus fully described my invention what I claim as new and desire to secure by Letters-Patent is;

An embroidery frame having secured thereto, metallic fastening members the ends thereof being slotted and having a portion of their slotted ends turned upwardly, combined with L-shaped members each provided with a central aperture in its body portion;

a bolt provided with a winged nut; said fastening members being operatively mounted on the ends of the end members of said frame to permit of said end members being
5 movably held in spaced relation to each other upon the side-members of the frame.

In testimony whereof I have signed my

name to this specification in the presence of two subscribing witnesses.

MATILDA ROSS.
